UNITED STATES PATENT OFFICE

NATHANIEL E. LOOMIS, OF WESTFIELD, AND LOUIS BURGESS, OF ROSELLE, NEW JERSEY, ASSIGNEES TO STANDARD OIL DEVELOPMENT COMPANY, A CORPORATION OF DELAWARE

ART OF CONVERTING OILS

Application filed May 7, 1927. Serial No. 189,476.

This invention relates to a method for converting hydrocarbon oils into lower boiling oils by heating such oils with aluminum chloride and more particularly by heating such oils in contact with aluminum chloride at higher temperatures than are possible under normal atmospheric pressures. This is a continuation in part of our prior co-pending application, Serial No. 532,839, filed January 30, 1922.

This invention has for its objects, among others, an increase in the amount of low boiling oils recoverable, an improvement in efficiency of the aluminum chloride catalyst and an increased output from apparatus of any given size. Other objects and advantages will be apparent from the specification.

The drawing which accompanies this application shows a vertical section of apparatus suitable for carrying the invention into effect. The numeral 10 designates a suitable still, preferably having a dished bottom and mounted in a suitable furnace setting 11. In the still is mounted a stirrer 12, which may suitably be of rectangular form. The stirrer is secured to the rotatable shaft 13, which passes through a stuffing box and journal 14 at one end and at the other end is mounted in a thrust bearing in a spider 15 secured to the bottom of the still. Dragging scrapers 16 are pivotally secured to the bottom reach of the stirrer 12, these scrapers covering substantially the entire bottom of the still on each rotation of the stirrer, in substantially the manner shown in the copending application of one of us Serial No. 183,285 filed April 13, 1927.

At the top of the still there is provided a suitable covered man-hole 17. In the bottom of the still is a discharge opening 18, which is normally closed by a valve 19 of the poppet type. Below the opening 18 is a discharge chamber of substantially cylindrical shape, to the wall of which is secured a guide 21 for the operating stem 22 of valve 19. The valve stem 22 is preferably formed with a rack, as illustrated, and is operated by means of a gear 23 mounted upon the shaft 24 which extends to the exterior of the furnace setting and is provided with a suitable

hand-wheel 25 or other operative device. At the lower end of the discharge chamber, a gate valve 26 is provided and below this is a receiving chamber 27.

An inlet pipe 28 opens into the lower portion of the still 10, and may be employed for the introduction of aluminum chloride vapors, or oil, or both. An oil supply pipe 29 opens into the lower portion of the discharge chamber which, during normal operation of the still, may be employed as a pre-heating chamber. The oil may be discharged through pipe 30, opening into the upper portion of the discharge chamber. Oil passing out of the chamber through the pipe 30 may be discharged into the still through the valved pipe 31 or may be introduced into the inlet pipe 28 through the pipe 32.

Vapors formed in the still pass out through the vapor line 33 into the down-flow vertical tubular condenser 34. From this the cooled gases and condensed liquids discharge through pipe 35 into the receiver 36. The gases separating in the receiver pass out through gas discharge line 37 provided with a suitable adjustable pressure release valve 38. A gas by-pass 39 provided with a valve 40 is provided around the pressure control valve 38. Condensed liquids in the drum 36 may be discharged through valved pipe 41.

We have found that in carrying out the distillation of oils in contact with a catalyst containing aluminum chloride, the efficiency of the catalyst can be materially increased by maintaining the oils in contact with the catalyst at higher temperatures than had been previously employed. These higher temperatures referred to are above the normal boiling point of the oil undergoing conversion and may even be as high as 700 or 800° F. although temperatures between 650 and 750° F. are ordinarily employed. Operation under these conditions is possible as we have discovered only by the application of considerable pressure to the materials undergoing decomposition. This pressure must be greater than the vapor pressure of the oil to be converted and less than the vapor pressure of the desired product at the temperature of conversion.

While our invention comprehends any application of pressure under the conditions referred to, our preferred method comprises the application of pressure to the method of distilling oils in contact with aluminum chloride outlined in application of one of us Serial No. 183,285, filed April 13, 1927. As specifically recited therein, this application comprehends a method of distilling oils in which the oil is held at a temperature at which a certain composition of distillate is produced. This composition of distillate is not pure gasoline, but such a ratio of gasoline, kerosene, and charge stock as will yield a maximum financial return when taking into account all of the factors connected with the operation of the process. When operating under the process referred to, aluminum chloride or a catalyst containing the same, is supplied to the still in a uniform and sustained manner at a rate proportional to the rate at which distillate is evolved, while oil is supplied to the still at a rate sufficiently to maintain the volume of still contents substantially constant.

In the present process the gage pressure is preferably 100 to 300 lbs. per square inch. Thus with a charge of gas oil at a temperature of about 700° F., an operating pressure of about 100# gage will ordinarily be sufficient, although if there is a tendency for the stock to yield a product different from that desired at the particular temperature, it can, of course be compensated for by modifying the pressure. An increase in pressure will effect a decrease in specific gravity and vice versa.

When operating on a charge consisting of hydrocarbon oils lighter than gas oil, for instance, kerosene distillate, higher pressures will be required to maintain the desired composition of distillate evolved and pressures in the neighborhood of 250# gage may ordinarily be required. It will, of course, be understood that the particular pressures mentioned should be sufficient to maintain the desired composition of evolved distillate, that any pressures necessary to this end, may be maintained and that the particular pressures mentioned are illustrative and not by way of limitation. We have, moreover, discovered that by the application of pressure in this manner, the rate at which the still can be operated is considerably increased. The tendency to the loss of aluminum chloride or aluminum chloride hydrocarbon compounds and charge stock from the still as a result of a mechanical transport is considerably diminished and the daily turnover from a still of a definite size can be considerably increased.

Having described our invention, we will proceed to describe a method of operating the same without limitation, however, as to the various other modes by which the described process can be carried into effect. Referring again to the drawing which accom-

panies the specification, the still 10 is charged about two-thirds full of the hydrocarbon to be decomposed. Heat is then applied by means of the burner shown. During the first period of heating, the by-pass valve 40 is preferably left open to permit the escape of air from the still. As soon as distillate begins to be evolved, this valve is closed entirely and the regulating valve 38 is set at a pressure of 100# gage. The liquid is then carried up to the desired temperature of operation which, with a charge of gas oil, may be assumed to be 700° F.

At this point, we commence feeding a mixture of oil and aluminum chloride hydrocarbons to the still through pipe 28. For large scale operation a plurality of such pipes is desirable for complete absorption of the chloride and efficient reaction. This feeding of aluminum chloride sets up a vigorous reaction in the still and produces an evolution of vapors which are condensed in condenser #34. The gravity of the distillate evolved is tested and if it is too light, the pressure is cautiously and slightly decreased. If it is too heavy, the pressure is conversely increased.

At this point, we commence feeding in an additional quantity of hydrocarbon oil in amounts such that the total feed will substantially compensate for the loss as distillate, together with the calculated loss of oil which is converted into stable sludge compounds and the amount lost as permanent gases. If the precise amount has not been previously determined, oil may be fed in at substantially the rate the distillate is evolved plus 2 or 3 per cent. Repeated tests are made on the distillate and the necessary pressure corrections are correspondingly made. During the first few hours of operation, a gradual change in pressure or temperature is necessary to hold the evolved distillate constant in composition, which is desirable. Petroleum oils consist of a number of different components of varying response to the catalytic activity of aluminum chloride. By the procedure just described, we cause those components which react with least avidity to accumulate in the still until they have increased in proportion, while those which react with the greatest avidity decrease correspondingly. The net result is to build up in the still such a proportion of components that in any unit of time, the components existing in the feed oil are decomposed in the same ratio as they are charged to the still.

During the first few hours of operation, this limiting condition is being continuously approached and at the end of a few hours, the charge will have come to a definite equilibrium and will not thereafter change in composition. From this point on, the various components existing in the oil fed to the still will be decomposed in the ratio in which they

respectively exist in the feed, with the production of a substantially uniform and unchanging composition of evolved distillate.

Under these conditions, it is quite feasible to take off 30 or 40 per cent per hour of the quantity of liquid in the still as distillate without undue mechanical transport of charge or loss of aluminum chloride. The rate at which distillate is evolved is a direct function of the rate at which the catalyst is supplied and subject to the limitation just expressed, may be controlled thereby. The particular rate of running mentioned will of course be understood as illustrative merely and not in any sense in limitation of that which may be practically maintained without departing from the process.

After operating in this manner for a considerable period, depending of course on the rate maintained, the amount of sludge which has accumulated in the still will be too great for the most economical operation, and at this point, the burner is shut off, the feeds are stopped and by proper manipulation of valves 26 and 21, a quantity of the sludge is withdrawn. It is desirable to keep the stirrer moving during this stage of the operation. As soon as this withdrawal has been accomplished, the burner is again turned on and the feed of oil and aluminum chloride is resumed. Distillation will proceed as before. It is of course necessary from time to time to withdraw condensate from receiver 36 by means of pipe 41 and this should be done so gradually as not to materially change the pressure.

We claim:

1. The method of converting oils to lower boiling oil products, which comprises heating the oil to be converted to a temperature above its atmospheric pressure boiling point and between 650° and 750° F., in the presence of active aluminum chloride, distilling the oil while maintaining pressure thereupon greater than its vapor pressure and less than the vapor pressure of the relatively light constituents at that temperature, and withdrawing vapors predominantly composed of the light constituents.

2. Process according to claim 1, in which the pressure is between 100 and 300 lbs. per sq. in.

3. The method of converting oils to lower boiling oil products, comprising heating the oil to be converted to a temperature above its atmospheric pressure boiling point and between 650 and 750° F., in the presence of active aluminum chloride, distilling the oil while maintaining pressure thereupon greater than its vapor pressure and less than the vapor pressure of the relatively light constituents at that temperature, withdrawing vapors predominantly composed of the light constituents, and controlling the pressure to

maintain the desired characteristics of the converted products.

4. The method of converting hydrocarbon oil into lower boiling oil products, which comprises heating said oil under pressure between 100 and 300 lbs. per sq. in. to a temperature above its atmospheric pressure boiling point and between 650 and 750° F., adding fresh oil at a rate sufficient to maintain the volume of still contents substantially constant, adding thereto a catalyst containing aluminum chloride in a uniform and sustained manner, at a rate sufficient to maintain the desired rate of evolution of distillate, modifying the temperature or pressure to the extent necessary to maintain a distillate of predominantly light constituents, until a condition of equilibrium is obtained, and thereafter continuing the operation under uniform conditions of temperature and pressure.
